[57] CLAIM

The ornamental design for a page holder for an open book, as shown and described.

DESCRIPTION

FIG. 1 is a front elevational view of a page holder for an open book, showing our new design, the opposite side being identical;

FIG. 2 is a top plan view thereof;

FIG. 3 is a bottom plan view thereof;

FIG. 4 is a right edge elevational view;

FIG. 5 is a front elevational view of a modified form of

the page holder for an open book, the opposite side being a mirror image thereof;

FIG. 6 is a top plan view thereof;

FIG. 7 is a right edge elevational view of the form of

FIGS. 5 and 6;

FIG. 8 is a front elevational view of another modified form of the page holder for an open book, the opposite side being identical; and

FIG. 9 is a right edge elevational view of the form of

FIG. 8.

The design is characterized by three top arcs substantially concentric with the inner concave arches, in combination with the inward inclination of the outer legs.
